UNITED STATES PATENT OFFICE.

WILLIAM W. LASKER, OF BROOKLYN, NEW YORK, ASSIGNOR, BY MESNE ASSIGNMENTS, TO POWERS ACCOUNTING MACHINE CORPORATION, OF NEW YORK, N. Y., A CORPORATION OF DELAWARE.

PAPER-SUPPORTING CARRIAGE AND GUIDING MEANS.

Original application filed March 28, 1917, Serial No. 158,142. Divided and this application filed February 1, 1918, Serial No. 214,852. Renewed February 27, 1924.

To all whom it may be concern:

Be it known that I, WILLIAM W. LASKER, a citizen of the United States, residing in Brooklyn, N. Y., in the county of Kings and State of New York, have invented certain new and useful Improvements in Paper-Supporting Carriages and Guiding Means, of which the following is a specification.

This invention relates to a printing tabulator of the kind adapted to be controlled by perforated cards, and relates more particularly to matter divided from my co-pending application Serial No. 158,142 filed March 28, 1917, for printing tabulators.

The invention herein described relates more particularly to the paper supporting carriage and the paper guiding means of said printing tabulator; and, therefore, only as much of the printing tabulator is described herein as is necessary to show the connection between the matter of the original application and the matter divided out.

While herein and in said application minute details of one of many possible embodiments of the invention are described, the invention is not limited to these since various changes may be made in the details of construction and combination without departing from the spirit and scope of the invention as claimed.

One object of the invention is to improve generally apparatus of this kind.

Another object of the invention is to provide an economical and efficient means for effecting the printing by the reciprocation of the paper carriage when the printing type have been set.

Another object is to provide convenient means for at will displacing the printing carriage laterally relative to the type so that substantially any part of the paper may be brought to the type.

Another object is to provide a new and improved method of mounting the paper supporting rolls.

Another object is to provide an economical and efficient platen for pressing the paper against the type.

Still further objects and advantages of the present improvement will be set forth in the following description and drawings in which,

Fig. 1 is an end elevation of a printing tabulator constructed in accordance with my invention.

Fig. 2 is a side elevation of the printing and calculating mechanism constituting a part of the printing tabulator.

Fig. 3 is an end elevation of the printing carriage showing one position of the parts.

Fig. 4 is a front elevation of the carriage.

Fig. 5 is a sectional view of the detail taken on the lines 5—5 of Fig. 4.

Fig. 6 is a fragmental end elevation showing parts of the paper feeding mechanism and the release of the same.

Figs. 7 and 8 show sections taken respectively on lines 7—7 and 8—8 of Fig. 4.

Fig. 9 is a face view of the print and non-print locking plate.

In said co-pending application, there is shown a printing tabulator which is adapted to be actuated by perforated cards, which in their passage through the machine operate elements for setting up type commensurate with the designations on the card and actuate an accumulating mechanism for accumulating therein the data recorded on the card perforations whereby the total accumulated data may be computed and then printed by the printing elements of the machine.

The embodiment comprises, as shown herein in a lower frame 1 (Fig. 1) in which the main driving shaft 2 is mounted, a card feeding mechanism, and a card analyzing mechanism; and an upper frame 5, in which the accumulating and printing mechanism are mounted.

The cards to be analyzed are disposed in a suitable receptacle and are fed by a card picker mounted at the bottom of such receptacle to the feed rollers 7, from which the card is fed between the die plate 8 and guide plate 9 in which position the several designations on the card register with the

pins 10 of the vertical reciprocatable pin box 11, which pin box is raised after a card is positioned between such plates 8 and 9 and the pins 10 which find perforations 5 in the card being analyzed pass upward therethrough and engage extension pins 12 which, in turn, will actuate registering stops. After the card has been so analyzed by the pins 10, it will be discharged into 10 a suitable receptacle.

Power is transmitted from the main drive shaft 2 to a shaft 17 by means of a transmission shaft 18.

The shaft 17 is provided with a plurality of cams from which are operated as explained in the co-pending application, the various mechanisms of the tabulating machine 19, of which it suffices here to say that these operate the type segments 20 20 (Fig. 2) so that the type 21 will be positioned to print items in accordance with the setting by the cards of the pins 10 and 12, and print the resulting totals, upon a sheet of paper brought against the type 25 25 by the printing carriage now to be described.

The printing carriage, designated generally by reference numeral 28 (Figs. 2, 3 and 4) is located on the rear of the printer 30 tabulator base, to the rear of the tabulating machine 19.

The carriage 28 which consists of mechanism for controlling the movement of the paper rolls and printing on the same is 35 mounted between two plates 47 which are tied together by means of tie-rods 48 and 49. Said carriage 28 is carried at each end on an L-shaped support member 35 which slides in a slot 34 in bracket 31 and 40 also has a roller 36 on the end of its horizontal arm which roller moves in an opening 37 formed in bracket 29. On the upper end of the vertical portion 38 of said member 35 is a connecting shaft 39. Mounted 45 on the shaft 39, between said members 38, are two levers 87 which are also mounted on a shaft 89 carried in bracket 31. These levers 87 serve in the manner to be later described to give a reciprocating motion to 50 the carriage so that it can be moved against the type sectors 21 in order to print.

Another pair of supports 42 which are approximately L-shaped, are connected near the upper ends of their vertical arms to shaft 39 between the two levers 87, and have forward extending arms 44 curved to come directly under the tie-rod 48 so that they support the tie-rod and the carriage. The supports 42 are mounted, at the point where the vertical and horizontal arms meet, on the shaft 40.

Two forwardly extending plates 45 are secured in slots in the shaft 39 and at their forward ends support a carriage rail 65 46 so that when shaft 39 is reciprocated by

movement of levers 87, carriage rail 46 will reciprocate with it.

Slidably mounted on carriage rail 46 are two plates 50 provided with slots 51 of such size as to permit the plates 50 to be 70 moved past plates 45 when these plates are rotated about 25° counter-clockwise from the position shown in Fig. 3. The plates 50 are connected with the carriage 28 by rods 49 and 69. It will thus be seen that 75 the carriage 28 is pivotally suspended at its rear on rail 46 and in front is supported by the contact of rod 48 with arms 44.

In the operation of the machine it is sometimes desirable to shift the carriage 80 longitudinally relatively to the type sector units, so that the printing columns may occupy various desired positions upon the sheet of paper. Means for accomplishing this will now be described:

The forward edge of the uprights 38 (Fig. 3) of the members 35 are provided with inwardly turned perforated ears 61 (Fig. 5) carrying supporting studs 62 on which is slidably mounted the locating bar 64 provided with elongated slots 65 receiving said studs 62, said bar 64 being also provided with a plurality of holes 66 large enough to receive the head of the locating stud 67 fixed on the locating bracket 68 fixed to the bracket shafts 69 (Fig. 6) connecting the end plates 47.

The stud 67 carried by bracket 68 is locked in position (see Fig. 5) by means of a locking plate 70 provided with key slots 71 each having a large end 72 thru which the head of the stud 67 is adapted to pass and with small ends 74 adapted to form shoulders to engage under the heads of said studs whereby the stud is locked in position by means of a spring 75 tensioned between the upright 38 and the angular manipulating end 76 bent outwardly from said locking plate.

The locking plate 70 is held in proper position by means of the guide plate 79 and 80, the guide plate 79 being secured to one of said ears 61 and engaging over the locking plate, the guide plate 80 being secured to the manipulating end 76 of the locking plate and provided with a slot 81 receiving a screw 82 secured to the adjacent ear 61.

To change the position of the carriage the locking plate 70 is pushed over to allow pin 67 to swing free of holes 71 and 66 after which the carriage 28 is swung up around rail 46 and then is moved along rail 46 until it reaches the desired location when the pin 67 is reinserted in a new hole 66 and locked 125 in place as desired.

The printing is accomplished by the forward movement of the paper supporting mechanism which movement brings the paper against type 21 of the type sectors. 130

- This is accomplished by means of the upper and lower carriage actuating levers 87 and 88 (Fig. 3) pivoted on the lever shaft 89 carried by the brackets 31. The upper and 5 lower actuating levers are both pivotally mounted on said shaft 89 and when in printing position are locked together as will be explained, and are oscillated by means of the engagement of the cam roller 90 engaging in 10 the cam groove 91 of the printing cam 92 carried on the cam shaft 17. The actuating levers give one complete cycle of oscillation once for every revolution of the cam shaft 17.
- 15 The locking above referred to is accomplished by means of locking cones 95 which are shown in unlocked position in Fig. 4 and must be moved to the right of said figure to lock said upper and lower levers against relative movement. These cones engage in, and when locked, hold in alignment the openings 98 and 99 of said upper and lower levers, and are carried on the cone supporting shaft 100 yieldably drawn to unlocked position by 20 means of the tension spring 101 secured between the end of said shaft and a cross piece 102 (Fig. 3) disposed across the opening 104 in the bracket 31. The opening 104 is large enough for the insertion of the cone shaft and cones when assembling the machine. These cones may be moved to locking position by means of the bell crank lever 105 fulcrumed on the base of the machine and provided at its upper end with spaced ears 25 106 engaging a transverse pin 107 in the cone supporting shaft 100. This lever is actuated by means of a link 108 pivoted at its lower end to said lever 105, and at its upper end to the locking lever 110 (Figs. 2 and 3) fulcrumed intermediately as at 111 on the cam shaft bracket 29. The locking lever 110 terminates in a manipulating end 112 (Figs. 2 and 9) received in a slot 114 of the locking plate 115, said slot being provided at its upper and lower parts with shoulder-forming recesses 116 and 117 in which said manipulating end may be locked to retain said locking cones in either locked or unlocked position. When lock lever 110 40 is moved into locking position, lever 87 will be moved by a movement of lever 88 and thereby the printing carriage will be moved and the items set up by type segments 21 will be printed.
- 45 Now will be described the means for supporting the paper on the carriage.
- On the paper roller shaft 60 journaled in the end plates 47 (Figs. 3 and 6) are disposed a plurality of paper engaging means or rollers 118 each provided with a boss 119 (Fig. 8). These bosses are held spaced apart by means of spacing bushings 120 (Fig. 7). Between adjacent pairs of the paper rollers 118 and loosely engaging said bushings are disposed platen support brack- 50 ets 121 held against rotation by means of the bracket shaft 122 (Fig. 6) passing thru holes in the lugs 123 on the upper part of said brackets and mounted in plates 47. Said brackets are held in spaced relation by means of sleeves 124 (Fig. 8) carried on said shaft 122. The lower part of each platen support bracket carries a forward projection 125 on which is secured as by means of a screw 126, the platen support 127 having a recess in its forward end in which is carried the elastic platen block 128 of rubber or other suitable material which forms a paper backing means for the paper when it is pressed against the type.
- 55 The bushings 120 hold the paper rollers out of frictional contact with the platen brackets. The bushings and the paper rollers and all the parts rotatable on the paper roller shaft 60 are caused to rotate with said shaft by means of frictional engagement with each other brought about by the clamping of the screw 129 (Fig. 3) on said shaft.
- Between each adjacent pair of paper rollers are the upper and lower inner paper shields 130 and 131 (Fig. 7) which form a continuation of the cylindrical surface of the paper rollers. These shields have angular extensions 134, each extension having inwardly turned ears 135 each provided with an opening receiving the bracket shaft 122. The upper inner shield 130 is pivotally supported on said rod by said ears, being permitted to move pivotally because of the rounded upper face 136, whereby access may be had to the screw 126. The upper shield 130 may be omitted if desired.
- 60 Partly surrounding or housing the lower inner shields 131 and the lower part of the paper rollers 118 are the outer paper shields 137 provided with edge flanges 138 on which are formed turned ears 139 provided with openings receiving the bracket shafts 69 (Figs. 3 and 7). These outer shields co- 65 operate with the lower inner shields 131 to form guides for the paper 140 on which the tabulations are to be printed. the outer shields being continued upwardly in front of the paper rollers 118, whereby are formed extensions 144 (Fig. 7) between which the type of the type sectors pass when the paper is pressed against them by means of the platen blocks 128.
- 65 On the lower part of the flanges 138 are formed small ears 145 provided with perforations in which are carried release arm shafts 146 (Figs. 6 and 7) on which are pivotally carried the feed roller levers 147 between the outer ends of which are journaled the paper feed rollers 148 said rollers engaging on opposite sides of the lower part of the paper rollers 118, and passing thru suitable openings in the lower shields 137. These feed rollers are held in contact with the paper rollers by means of feed roller 70 149.

tension spring 149 secured at opposite ends to the journaled pins 150 of the rollers (Fig. 6).

The pressure of rolls 148 on the paper 140 may be released by means of a lever 156 which comes into contact with a rod 154 sliding in slots 155 of end plates 47. The lever 156 pushes up on end pieces 152 located at each end of levers 147, thereby 10 swinging rollers 148 out of the position shown in dotted lines in Fig. 6. The shaft 157 to which levers 156 are fastened is carried between end plates 47 and has directly connected to it a lever 158 which is manually operated to release the pressure on the rollers as described. When lever 158 is released, toward movement of this lever is limited by projecting portion 160 of plate 47 (see Fig. 3).

20 After each number is printed by the type of the type sectors, it is necessary to feed the paper upwardly one or more spaces. This feeding is accomplished by means of engagement of the teeth of the feed ratchet 161, mounted on the shaft 60 by a two armed feed pawl 162 (Fig. 3) pivotally mounted on the feed pawl lever 164 fulcrumed intermediately as on the stud shaft 165 and driven by the link 166, which in turn is driven by the drive lever 167 mounted on the lever shaft 168, said shaft being actuated by the actuating arm 169 fixed on said shaft and adapted to come into contact with and be moved by the abutment shaft 170 carried on the abutment shaft bracket 171 pivotally mounted on plates 32 which are suspended between brackets 29 and 31. The brackets 171 are limited in their rearward movement by the engagement with the tie plates 32 of a lug 174 laterally turned at the rear edge of said abutment shaft brackets, and is yieldably held at its rearward limit of movement by a spring 175 tensioned between said lug 174 and a lug on the rear part of the shaft plate 32.

When the carriage is moved forwardly toward the type sectors the free end face 176 of the actuating arm 169 engages and pushes back the abutment shaft 170 against the action of the spring 175 until said end face clears said shaft and permits the shaft and its bracket to be snapped back by the spring 175 until stopped by the shoulder 172.

50 After the printing has taken place and the carriage moved rearwardly, the abutment shaft 170 is engaged by the lower side of the actuating arm 169 whereby said arm and drive lever 167 are raised thus rocking the pawl lever 164 and lowering the pawl 162, which turns the ratchet 161 and moves paper 140 ahead one space.

The feeding mechanism is returned to position by means of a spring 185 tensioned 60 between the end plate 47 and a perforated

ear on the upper part of the inner end of the arm 167.

For removing or feeding paper entirely independently of the feeding mechanism, I provide the paper feed gear 189 fixed on the paper feed shaft 60 and engaged by the idler gear 190 rotatably mounted on the end plate 47 the idler gear being in turn engaged by the knob gear 191 fixed on the stud shaft 165 rotatably mounted in the end plate 47 and carrying knurled knob 192 by which said shaft and gears may be manually rotated.

While the paper is being fed and during the time of printing, it is desirable that it be firmly held against the platens 128. This is accomplished by means of a clamping mechanism comprising a clamp bar 193 (Fig. 3) carried between the outer ends of the clamping levers 194 provided with intermediate longitudinal slots 195 loosely receiving the paper feed shaft 60, whereby the paper clamp bar is adapted to move toward and from the paper rollers 118 as well as to pivot in relation to said rollers. The inner ends of the clamp levers are provided with small pins 196 received in longitudinal slots 197 in the lower ends of the spring levers 198 intermediately fulcrumed on the end plates 47 and drawn by a spring 199 strained between the upper end of the spring levers 198 and the upper part of end plates 47, whereby the clamp lever 194 is yieldably drawn downwardly and the clamp bar 193 is yieldably pressed against the paper and the paper pressed against the paper rolls 118.

This yieldable engagement maintains during the printing and feeding of the paper, but after feeding has taken place, as above described, the releasing pin 200 mounted on the cam bracket shaft 201 comes into contact with the abutment shaft 170 and forces the cam bracket shaft and the cam bracket 202 to rock rearwardly whereupon the cam edge 203 forces outwardly the pin 196 and therewith the lever 194 and bar 193 and also rocks said lever in a direction clockwise on Fig. 3 whereupon the bar 193 is moved downwardly over the paper and later takes a fresh grip upon the paper when the clamping lever is released by the cam on the next forward movement of the carriage and moves downwardly under the action of the spring 199.

The upper part of the cam brackets 202 are each provided with an outwardly projecting ribbon feed arm 204 (Fig. 3) for operating the feed mechanism of the ribbon spools of the ribbon 205 (Fig. 4); but as these form no part of the invention claimed herein they are not now further described.

When a total is printed it is desirable to show some visual signal to indicate that the number printed is a total. This is accomplished by shifting the carriage to the left

when the total is printed, whereby the total is shown printed a little to the right of the alignment of the listed column.

Means for accomplishing this result will now be described.

As shown in Fig. 4, the lower edge of the locating bar 64 is provided with a notch 240 in which engages the upper end of the vertical lever 241 pivoted intermediately on the bracket 242 fixed on the printing lever shaft 89, the lower end of said lever being pivotally connected to the rear end of the horizontal lever 244 (Fig. 3) intermediately pivoted on a pin 245 in a lug 246 on the base of the machine. The forward end of said horizontal lever is pivotally connected to the rear end of the total shift lever 252.

When the total pin 253 engages in the appropriate groove, after being manually released said pin is shifted to the right and a total is set up on the type 21 as explained in said copending application and the upper end of the lever 242 is shifted to the left whereupon the locating bar 64 is moved to the left on the pin 62 in the slot 65, thus causing the printing to take place a slight distance to the right of the column.

When by means of the lever 110 the carriage has been set to a non-printing position so that the items accumulated and set up by the type 21 are not printed, it is still desirable that the totals themselves be printed. In order to accomplish this printing automatically, there is provided the automatic printing lock lever 257 (Fig. 4) pivotally mounted on the bracket 258 fixed to the shaft 89 the upper end of which lever engages in a notch 260 the lower end engaging a transverse pin 261 in the printing lock shaft 100. When the carriage is shifted to the left, the bar 64 is moved therewith and carries the upper end of the lever 257 to the left whereupon the lower part of said lever, said printing lock shaft and the cones 95 are moved to the left thus locking together the upper and lower printing levers 87 and 88 and effecting the printing.

From the foregoing, the operation of the printing carriage will be easily understood. Paper is inserted in the rear opening between the outer shields 137 and the inner lower paper shields 131, and the paper rolls 118 turned by means of the knob 192 until the part on which it is desired first to print are opposite the platen blocks 128. If desired, the locking plate 70 is unlocked and the carriage adjusted on the carriage rail and the carriage relocked.

The locking lever 110 is set in locked or unlocked position depending upon whether it is desired that the items be printed or not.

The tabulating machine is then started in operation as explained in the said copending application and the type is set and the ac-

cumulators accumulate. If the locking lever is set in locked position the cams 92 cause the printing levers and the carriage to reciprocate and the printing is effected.

When a total is taken the carriage is moved to the left just before the printing by means of the total signal lever 241 engaging in the notch 240 of the locating bar. If the locking lever 110 has not been set in printing position, the automatic levers 257 also cause the cones 95 to lock the printing levers and print totals when the totals are set up and printed.

I claim:

1. In an apparatus of the character described, the combination of a carriage support; a paper support slidable and swingable on said carriage support and adapted to be moved into and out of locking engagement therewith.

2. In an apparatus of the character described, the combination of printing means; a carriage support adapted to be reciprocated toward and from the printing means; a carriage rail supported on the carriage support; a paper support slidable on said rail; and means interposed between said support whereby the paper support may be swung into and out of locking engagement with the carriage support.

3. In an apparatus of the character described, the combination of printing means; a carriage support adapted to be reciprocated toward and from the printing means; a carriage rail supported on the carriage support; a paper support slidable and adapted to swing on said rail; a locating bar mounted on one of said supports and provided with a plurality of openings; and plurality of locating brackets mounted on the other support and adapted to engage in and be locked in said holes.

4. In an apparatus of the character described, the combination of a carriage support; a carriage rail; means supported on the carriage support and supporting said rail; and a carriage comprising parts provided with an opening receiving said rail and a slot furnishing passage for said means.

5. In an apparatus of the character described, the combination of printing means; a carriage support adapted to be reciprocated toward and from the printing means; a carriage rail; rail supports supported on the carriage support and supporting said rail; a paper carriage; and rail engaging brackets on said carriage and each provided with an opening receiving said rail and a slot furnishing passage for the rail supports for permitting the carriage to be slipped off the end of the rail.

6. In an apparatus of the character described, the combination of printing means; a carriage support adapted to be reciprocated toward and from the printing means;

- a rod like carriage rail; a pair of thin rail supports fixedly supported on the carriage support and fixedly supporting said rail; a paper carriage; rail engaging brackets fixed on said carriage each provided with an opening receiving said rail and a slot communicating with the opening and furnishing passage for the rail supports; and means for locking the carriage to the support.
7. In an apparatus of the character described, the combination of printing means; a carriage support adapted to be reciprocated toward and from the printing means; a carriage rail; rail supports supported on the carriage support and supporting said rail; a paper support, rail engaging brackets fixed on said paper support each provided with an opening receiving said rail and a slot communicating with the opening and furnishing passage for the rail supports, said brackets being slideable and swingable on said rail; a locating bar mounted on one of said supports and provided with a plurality of openings; and plurality of locating brackets fixed on the other support and adapted to engage in and be locked in said holes.
8. In an apparatus of the character described, the combination of printing means; a paper carriage support adapted to be reciprocated toward and from the printing means; a rod like carriage rail; a pair of thin rail supports fixedly supported on the carriage support and fixedly supporting said rail; a paper carriage; rail engaging brackets fixed on said carriage each provided with an opening receiving said rail and a slot communicating with the opening and furnishing passage for the rail supports, said brackets being slideable and swingable on said rail; a locating bar mounted on said carriage support and provided with a plurality of openings; and plurality of locating brackets fixed on the carriage and adapted to engage in and be locked in said holes.
9. In an apparatus of the character described, the combination of a printing lever; a reciprocating support having one end pivotally connected to said lever; means slidably supporting the opposite end of said support; paper carrying means carried on said support; and means cooperating with said carrying means for effecting printing.
10. In an apparatus of the character described, the combination of a printing lever; a cam for oscillating said lever; a reciprocating support having one end connected to said lever; means slidably supporting the opposite end of said support; paper carrying means carried on said support; and means cooperating with said carrying means for effecting printing.
11. In an apparatus of the character described, the combination of a rotary cam; a printing lever shaft; a printing lever car-
- ried on said shaft and engaging said cam; a carriage adapted to be reciprocated by said lever; paper carrying means on said carriage; and printing means against which said paper and said carriage are adapted to be brought.
12. In an apparatus of the character described, the combination of a rotary cam; a printing lever operated by said cam; a reciprocating bracket having one end pivotally connected to said lever; a stationary bracket slidably engaging and supporting the other end of said reciprocating bracket; a paper supporting carriage carried on said reciprocating bracket; and printing means against which said carriage is adapted to be brought.
13. In an apparatus of the character described, the combination of a reciprocating support; a paper carrying support; means slidably connecting said supports together; and means toward which said paper carrying support is reciprocated for effecting printing.
14. In an apparatus of the character described, the combination of a reciprocating support; a paper carrying support; means slidably connecting said supports together in different positions; means for locking said supports in said different positions; and means toward which said paper carrying support is reciprocated for effecting printing.
15. In an apparatus of the character described, the combination of a reciprocating support; a paper carrying support; a rail carried by one of said supports; means carried by the other support and slidably engaging said rail; and means toward which said paper carrying support is reciprocated for effecting printing.
16. In an apparatus of the character described, the combination of a reciprocating support; a paper carrying support; a rail carried by one of said supports; means carried by the other support and slidably engaging said rail for connecting said supports in different relations; locking means for locking said supports in said different relations; and means toward which said paper carrying support is reciprocated for effecting printing.
17. In an apparatus of the character described, the combination of a reciprocating support; a paper carrying support; means for slidably connecting said supports to each other; a bar carried by one of said supports and having holes therein; a locking plate provided with key slots adapted to register with said holes and each having a large end and a small end, said small end forming shoulders; a stud carried by said other support and having a head adapted to pass thru said holes and said large ends and under which said shoulders are adapted to

engage, whereby said stud is locked; and means cooperating with said paper carrying support for effecting printing.

18. In an apparatus of the character described, the combination of a pair of supporting elements; a carriage rail supported on said elements; a locating bar supported on said elements and provided with a plurality of holes; a paper carriage slidably supported on said rail; a head stud carried on said carriage and adapted to engage in said holes; and a locking plate provided with key slots forming shoulders adapted to engage under said head and lock said stud in said holes.

19. In an apparatus of the character described, the combination of a reciprocating support; a paper carrying support; a rail carried by one of said supports; means carried by the other support and slidably engaging said rail for connecting said supports in different relations; a bar carried by one of said supports and having holes therein; a locking plate provided with key slots adapted to register with said holes and each having a large end and a small end forming shoulders; a stud carried by said other support and having a head adapted to be engaged and locked by said shoulders; and means cooperating with said paper carrying support for effecting printing.

20. In an apparatus of the character described, the combination of a rotatable shaft; a series of spaced paper engaging means on said shaft adapted to carry paper; means carried on the shaft at the ends of the shaft and interposed between and spacing said paper engaging means for holding by frictional engagement the shaft and the parts carried thereon against relative rotation; means supporting said shaft; and means cooperating with the paper and said supporting means for effecting printing.

21. In an apparatus of the character described, the combination with printing means of a rotatable shaft; paper engaging means on said shaft; a nonrotatable paper backing means; means for holding by frictional engagement with each other said shaft and the parts thereon against relative rotation during printing; means supporting said shaft; and means cooperating with the backing means and said supporting means for effecting printing.

22. In an apparatus of the character described, the combination with printing means of a rotatable shaft; paper engaging means on said shaft; a paper backing means; means carried on said shaft for spacing the engaging means; means for holding said shaft and the parts thereon in frictional engagement during printing; means for supporting said shaft; and means cooperating with the backing means and said supporting means for effecting printing.

23. In an apparatus of the character described, the combination with printing means of a rotatable shaft; means carried thereon for rotating the shaft; paper engaging means on said shaft; nonrotatable paper backing means; means for holding said shaft and the parts thereon in frictional engagement during printing; means for supporting said shaft; and means cooperating with the backing means and the supporting means for effecting printing.

24. In an apparatus of the character described, the combination with printing means of a rotatable shaft; drive means carried thereon for rotating the shaft; a plurality of paper engaging means on said shaft; means for spacing said engaging means; paper backing means disposed between the engaging means; means for holding said shaft and the parts thereon in frictional engagement during printing; means for supporting the shaft; and means cooperating with the backing means and the supporting means for effecting printing.

25. In an apparatus of the character described, the combination of a plurality of paper engaging means; paper backing means disposed between said engaging means; means for supporting said engaging means and backing means; and means cooperating with said supporting means and said backing means for effecting printing, said engaging means coming into actuation when said printing takes place.

26. In an apparatus of the character described, the combination of a rotatable shaft; paper rolls fixed on said shaft; paper backing means disposed between said rolls; means for supporting said shaft and backing means; and means cooperating with said supporting means and backing means for effecting printing, said engaging means coming into actuation when said printing takes place.

27. In an apparatus of the character described, the combination of a rotatable shaft; paper rolls on said shaft; spacing means disposed between said rolls; paper backing means disposed between said rolls; means for supporting said shaft and said backing means; and means cooperating with said supporting means and said backing means for effecting printing.

28. In an apparatus of the character described, the combination of a rotatable shaft; paper rolls on said shaft; bushings on said shaft for holding said paper rolls spaced apart; paper backing means disposed between said rolls; means for supporting said shaft and backing means; and means cooperating with said supporting means and said backing means for effecting printing.

29. In an apparatus of the character described, the combination of a shaft; paper rolls on said shaft; bushings on said shaft

- for holding said paper rolls apart; brackets disposed between said rolls and engaging around said bushings; means for supporting said shaft and brackets; platens carried on said brackets; and means cooperating with said supporting means and platens for effecting printing.
30. In an apparatus of the character described, the combination of a shaft; paper rolls on said shaft; brackets disposed between said rolls and provided with forwardly projecting ends; platen supports received and supported by said ends; elastic platen blocks carried in said supports; means for supporting said shafts and brackets; and means cooperating with said supports and brackets for effecting printing.
31. In an apparatus of the character described, the combination of a shaft; paper rolls on said shaft; bushings on said shaft for holding said paper rolls spaced apart; brackets disposed between said rolls and provided with openings receiving said bushings; platen supports receiving and supported by the forward end of said brackets; elastic platen blocks carried in said supports; means for supporting said shaft and brackets; and means cooperating with the supporting means and the platens for effecting printing.
32. In an apparatus of the character described, the combination of a shaft; paper rolls fixed on said shaft; shields disposed between said rolls and forming therewith cylindrical surfaces; paper backing means disposed between said rolls; means for supporting said shaft; said shields, and said backing means; and means cooperating with said supporting means and said backing means for effecting printing.
33. In an apparatus of the character described, the combination of a shaft; paper rolls on said shaft; brackets disposed between said rolls and having forwardly projecting ends and rearwardly projecting ends; platen blocks supported on the forwardly projecting ends; a bracket shaft passing thru said rearwardly projecting ends; means for supporting said shafts; and means cooperating with said platen blocks and the supporting means for effecting printing.
34. In an apparatus of the character described, the combination of a shaft; paper rolls on said shaft; brackets disposed on said shaft between said rolls and having projecting ends; a bracket shaft passing thru certain of said projecting ends; platen blocks mounted on other of said ends; inner shields disposed between said rolls and mounted on said bracket shaft; means for supporting said shafts; and means co-operating with the supporting means and said blocks for effecting printing.
35. In an apparatus of the character described, the combination of a shaft; paper rolls on said shaft; brackets disposed on said
- shaft between said rolls; a bracket shaft passed thru said brackets; platen blocks supported on said brackets; upper and lower shields housing said brackets and each provided with perforated ears receiving said bracket shaft; means for supporting said shafts; and means cooperating with the supporting means and said blocks for effecting printing.
36. In an apparatus of the character described, the combination of a shaft; paper rolls on said shaft; brackets disposed on said shaft between said rolls; a bracket shaft passed thru said brackets; platen blocks supported on said brackets; upper and lower shields housing said brackets and each provided with perforated ears receiving said bracket shafts, the upper shield being pivotally mounted; sleeves on said bracket rod for holding said shields spaced apart; means for supporting said shafts; and means cooperating with the supporting means and said blocks for effecting printing.
37. In an apparatus of the character described, the combination of a shaft; paper rolls on said shaft; brackets disposed on said shaft between said rolls; a bracket shaft passing thru said brackets; upper and lower shields housing said brackets and each provided with perforated ears embracing said brackets and receiving said bracket shaft; a platen block mounted on each bracket; end plates supporting said shafts; supporting means for said end plates; and means cooperating with said blocks and supporting means for effecting printing.
38. In an apparatus of the character described, the combination of a rotatable shaft; paper rolls carried thereon; a plurality of levers fulcrumed near said paper rolls and extending in opposite directions; feed rolls journaled on said levers; a pair of end plates supporting said shaft and provided with vertical slots; a rod received in said slots and engaging said levers for releasing the feed rolls from the paper rolls; and means for actuating the rod.
39. In an apparatus of the character described, the combination of a rotatable shaft; paper rolls thereon for carrying paper; paper backing means disposed between said rolls; inner shields forming continuation of such rolls; and outer shields housing the lower part of said rolls and inner shields.
40. In an apparatus of the character described, the combination of a rotatable shaft; paper rolls thereon for carrying paper; paper backing means disposed between said rolls; inner shields forming cylindrical surfaces with said rolls; and outer shields housing the lower part of said rolls and inner shields and extending upwardly between said paper backing means.
41. In an apparatus of the character described, the combination of a shaft; paper

- rolls thereon for carrying paper; outer shields housing the lower part of said rolls and provided with perforated flanges provided with ears; bracket shafts extending 5 thru said ears and supporting said shields; and means for supporting said shafts.
42. In an apparatus of the character described, the combination of a shaft; paper rolls thereon; outer shields housing the lower part of said rolls and provided with perforated flanges; levers pivoted to said flanges; feed rolls carried by said levers; shafts passing thru said flanges and supporting said shields; end plates supporting said 10 shafts and provided with vertical slots; release rods disposed in said slots and engaging said levers; and actuating means engaging said release rods.
43. In an apparatus of the character described, the combination of a rotatable shaft; a plurality of paper rolls thereon for carrying paper; and inner shields between said rolls and forming cylindrical surfaces continuous with said paper rolls.
44. In an apparatus of the character described, the combination of a rotatable shaft; a plurality of paper rolls thereon for carrying paper; and inner shields forming cylindrical surfaces with said paper rolls.
45. In an apparatus of the character described, the combination of paper rolls; printing means; levers fulcrumed near said paper rolls and extending in opposite directions; means for moving said paper rolls toward said printing means for printing; feed rolls having journals journaled on said levers; springs tensioned and connected directly between said journals; and means for actuating the levers.
46. In an apparatus of the character described, the combination of a carriage support; a rail supported thereon; a carriage provided with a part having an opening receiving said rail for supporting the carriage, said part being adapted to be slipped off at the end of the rail and means for positively locking the carriage on the rail against end-wise movement in either direction without detaching said rail.
47. In combination, a plurality of printing means adapted for simultaneous printing; a support; a paper carriage longitudinally adjustable on said support; means for positioning and locking said carriage in adjusted position and means for reciprocating said support toward the printing means for effecting the simultaneous printing.
48. In combination, groups of printing means laterally spaced apart and adapted for simultaneously printing; a support; a paper carriage longitudinally adjustable on said support multiples of the distance from one to another of said groups; means for positioning and locking said carriage in its adjusted position; and means for reciprocating said support for effecting said simultaneous printing.
49. In combination, a mechanism provided with a movable type carrier; a carriage associated with said type carrier whereby printing is effected; means for carrying a ribbon between said carrier and carriage for reciprocating said ribbon away out of reach of said type; and means positioning said type when the ribbon is thus out of reach.
50. In combination, a tabulating mechanism provided with a plurality of movable type arranged for simultaneous printing in a straight line; a carriage reciprocatory to and from said type; means carried on the carriage for carrying a ribbon between said carriage and type; said ribbon being reciprocatory with said carriage away out of reach of said type; and means positioning said type when the ribbon is thus out of reach.
51. In combination, a tabulating mechanism provided with a movable type carrier carrying a plurality of type confined to the same path; a carriage reciprocatory to and from said type; means carried on the carriage for carrying a ribbon between said carriage and type; said ribbon being reciprocatory with said carriage away out of reach of said type; and means positioning said type when the ribbon is thus out of reach.

WILLIAM W. LASKER.
